UNITED STATES PATENT OFFICE.

ABRAHAM G. JENNINGS, OF BROOKLYN, NEW YORK.

DESIGN FOR ORNAMENTAL FABRIC.

SPECIFICATION forming part of Design No. 24,560, dated August 13, 1895.

Application filed June 28, 1895. Serial No. 554,138. Term of patent 14 years.

To all whom it may concern:

Be it known that I, ABRAHAM G. JENNINGS, a citizen of the United States, residing at Brooklyn, county of Kings, and State of New York, have invented and produced a new and original Design for Ornamental Fabric, of which the following is a specification.

The leading feature of my design is an ornamental fabric of essentially the ornamentation and representation exhibited in the accompanying drawing, which shows a section of fabric embodying my design.

In the drawing, A is the fabric, and B is a border therefor.

The design is as represented, consisting of a fabric A, exhibiting the dark irregular polygons *a a*, each presenting a tufted appearance or effect, alternated with the contrasting

lighter irregular polygons *b b*, also presenting a tufted appearance or effect, the general effect of the tufted appearance of the polygons *a a* being to produce an apparent overhanging of the edges *c c* of the polygons *a* over the borders or edges *d d* of the polygons *b*, thus partially obscuring the polygons *b b* and lending to the polygons *a a* an appearance or effect of being larger than they really are.

What I claim is—

The design for an ornamental fabric substantially as described and shown in the accompanying drawing.

ABRAHAM G. JENNINGS.
